UNITED STATES PATENT OFFICE.

WASILI PICHNO, OF KIEV, RUSSIA.

SPADE-PLOW.

SPECIFICATION forming part of Letters Patent No. 476,684, dated June 7, 1892.

Application filed February 26, 1892. Serial No. 422,886. (No model.)

To all whom it may concern:

Be it known that I, WASILI PICHNO, a subject of the Emperor of Russia, residing at Kiev, Russia, have invented certain new and useful Improvements in Spade-Plows, of which the following is a specification.

The present invention relates to a plow in which the plowshare is in the shape of a vertical concavo-convex disk, which turns the furrow by revolving under the traveling action of the carriage. The plowing effect may be increased by providing the share peripherally with a series of spades.

In the accompanying drawings, forming a part of this specification, Figures 1, 2, and 3 are a side, plan, and longitudinal section, respectively, of a plow embodying my improvements. Figs. 4, 5, and 6 are a vertical section side, and rear view of the plowshare and parts more immediately connected therewith.

The beam *a* is fastened below the axle *d*, and upon the ends of the latter are mounted the carrying-wheels *b* *c*. Fastening to the beam *a* by screw-bolts *e* *f* is a plate *g*, the bolt *e* forming a pivot for the same, while the bolt *f* admits of the adjustment of the plate by playing in a segmental slot in the same. The vertical concavo-convex plowshare *l* is provided peripherally with a series of spades *m*, and said share *l* is suspended from the plate *g* through the medium of a horizontal stub-shaft *k*, carrying at one end plate *n*, rigidly bolted to said share at the rear thereof, said shaft *k* bearing in boxes *p* connected to the plate *g*. By loosening the screw *f*, moving plate *g*, and again tightening said screw the plowshare *l* can be adjusted to occupy a greater or less lateral inclination relative to the longitudinal axis of the machine. On the carriage, in the rear of the axle *d*, a tool-box *r* is mounted, the cover *s* of which forms a seat for the driver.

In use the plowshare *l* must be set so that its shaft will be at an angle relative to the

axle *d*, so that the lowest spade *m* will be in alignment with the furrow. As the machine moves forward the spades successfully cut into the earth and turn a furrow, the displaced earth being forced upward against the front curved face of the share and dropped over in a turned position to one side. The bracket *t*, through the medium of the transverse bolts 1 and 2, admits of the tongue 3 being adjusted to different heights, and consequently vary the position of the plow *l* to cause it to cut deeper or shallower, as may be found desirable. It will be understood that the concavo-convex plowshare may be used minus the spades.

I claim—

1. In a plow, the combination of a supporting-frame, a horizontal adjustable plate secured thereto to rock on bolt *e*, means, substantially as described, for clamping said plate in the desired adjustment, the stub-shaft mounted in the boxes carried by said plate, and the concavo-convex disk rigidly secured on one end of said shaft, substantially as set forth. 60

2. In a plow, the combination of the wheeled supporting-frame, a plate secured thereto and horizontal adjustable means for clamping the plate in the desired adjustment, boxes carried by said plate, a stub-shaft mounted in said boxes and provided with a plate *n*, rigid on one end, the concavo-convex disk *l*, rigidly secured to said plate *n*, and the inclined spades rigid with and projecting from the edges of said disk, substantially as set forth. 70

In testimony whereof I have signed my name to this specification in the presence of two subscribing witnesses.

WASILI PICHNO.

Witnesses:

W. FRISK,
C. N. MANACPRULZ.
